WILLIAM D. HAILES, OF ROCHESTER, NEW YORK, ASSIGNOR TO GENERAL RAILWAY SIGNAL COMPANY, OF ROCHESTER, NEW YORK

TRAIN-CONTROL SYSTEM FOR RAILROADS

Application filed April 18, 1927. Serial No. 184,675.

This invention relates, in general, to train control systems, and has more particular reference to an intermittent inductive alternating current type of system employing car-carried receivers and traffic controlled wayside inductors.

In systems of the character in question, it is usual to control a train control device by means of influences inductively received by car-carried receivers from trackway inductors controlled in accordance with traffic conditions ahead. In such systems it is quite essential that the co-action between the inductors and receivers be uniform and certain and free from failures on the side of danger due to crosses and the like.

With the above and other considerations in mind, it is proposed, in accordance with this invention, to provide an improved type of trackway inductor and car-carried receiver satisfying the above requirements.

Further objects, purposes, and characteristic features of the invention will appear as the description progresses, reference being had to the drawing, showing solely by way of example, one form which the invention can assume.

In the drawing:—

Fig. 1 is a schematic representation of one form of the invention as applied to a simplified type of control means;

Fig. 2 is a top plan view of a receiver in accordance with this invention;

Fig. 3 is a side elevational view of the receiver;

Fig. 4 is a bottom plan view of the receiver, with parts broken away to more clearly show the construction;

Fig. 5 is an end view of the receiver of Fig. 3; and

Fig. 6 is a sectional view on line 6—6 of Fig. 3, viewed in the direction of the arrows.

Referring to the drawing, and first more particularly to Fig. 1, a stretch of trackway is shown comprised by track rails 1, separated in the usual manner by insulating joints 2, into signalling blocks, each block having a track battery 3 at its exit end, a track relay 4 at its entrance end and a wayside signal 5, shown as of the semaphore type, but which obvious-

ly could be of any other desired type. The various control circuits and devices for the wayside signals have not been shown as it is deemed unnecessary for the thorough understanding of this invention.

In front of the entrance end of each block is an inductor I comprising a magnetic core 6, preferably of laminated material, carrying a winding 7, connected in series with a tuning condenser 8 and a contact finger and front contact 9 of the adjacent track relay 4 whereby the winding 7 is open circuited when the relay is de-energized, as it is under danger conditions, and is closed circuited when the relay is energized, as it is under clear conditions. While the control for the winding 7 has been shown to comprise only danger and clear controls, it is obvious that the circuit in question could include a contact finger and front contact of a line relay controlled by traffic conditions in the second block ahead, whereby to give three controls for the winding 7, namely, open circuited for danger and caution, and closed circuited for clear conditions. A control, in this connection, such as shown in the W. K. Howe Patent, Ser. No. 1,604,098 of October 19, 1926, could be used.

Carried on the car, represented diagrammatically by the wheels and axles 10, is a receiver R, comprising a primary core 11, and a secondary core 12, formed of magnetic material and preferably laminated.

The primary core 11 is in the form of a bar with its ends 13—13' (see Fig. 3) bent downwardly at right angles to the body thereof, such ends carrying primary windings 14—14' connected in series with each other, with a tuning condenser 15, and a source of alternating current 16, preferably of a higher than the usual commercial frequencies such for example as 360 cycles per second.

The secondary core 12 is in the form of an H and carries a secondary winding 17 on the cross bar of the H, which is connected in series with a tuning condenser 18, and a main relay MR, the main relay having a contact finger 19, and front contact which controls an energizing circuit, including a source of potential 20, for a train control device, EPV, which is normally energized and which,

upon dc-energization, gives an automatic brake application or in some other manner initiates a train control influence. Each leg of the H shaped secondary core, 12 has one end bent downwardly at right angles to the main portion thereof, while the other end is straight, the straight end of each leg being opposite to the front end of the other leg. The secondary core is positioned below the main part of the bar forming the primary core, and within the primary core, as shown in Fig. 3, with the straight ends of the legs of core 12 extending further towards the ends 13, 13' of primary core 11, than do the downwardly bent ends of the legs, while the extremities of the downwardly bent ends are positioned in substantially the same plane as the ends of the downwardly bent parts 13, 13' of the primary core.

In operation the receiver R is positioned on the car to pass directly above the inductor I at the entrance to each block, and to communicate therewith through an air gap in somewhat the manner shown in Fig. 3, where by, if the signal block in question be clear, the coil 7 on the inductor is included in a closed circuit so that the choking effect of this coil effectually prevents any material flow of flux through the core 6, whereby the inductor has no more influence on the receiver than if it were not present.

On the other hand, if the winding 7 of the inductor be open circuited, such winding has no choking effect whatsoever, since no current can flow therein, so that the core 6 affords a good path for flow of flux and changes to the flux distribution in the receiver. As shown in Figs. 1, 2 and 3 by the full line arrows, the flux produced by the primary windings 14 and 14', flows in the direction indicated to thereby induce a voltage in the secondary winding 17 to cause current to flow through the main relay MR and maintain the energizing circuit for EPV closed. When the receiver, however, is above an inductor in its active or open-circuited condition, a second path is afforded for the flow of flux, as indicated by the dotted line arrows, which, it will be noted, tends to cause passage of flux through the secondary winding 17 in the opposite direction to that first considered. The various parts are so proportioned, and positioned, as to make the magnetic reluctances of these two magnetic paths substantially equal, whereby the active inductor produces a condition of substantially no flux flowing through the secondary winding 17 of the receiver, with a resultant de-energization of relay MR, and, for example, an automatic brake application due to de-energization of EPV. If the reluctances in question are not exactly equal a small induced current will then flow in the main relay MR in one direction or the other, but will be insufficient to energize relay MR.

The path taken by primary flux, in the absence of an inductor, can be readily traced, in Fig. 3, by following the full line arrows, from which it is seen that such flux passes from the primary core to the straight end 79 of one leg of the H shaped secondary core, through the cross bar and the straight end of the other leg, and back to the primary core. When an inductor is below the receiver, as indicated in dotted lines in Fig. 3, the path 75 taken can be traced by following the dotted line arrows, and passes from one bent end of the primary core to a bent end of one leg of the secondary core, then through the cross bar and down through the bent end of the 80 other leg of the secondary core and through the inductor to the other bent end of the primary core. This affords two paths for the 85 flow of flux, which pass through the secondary winding 17 in opposite directions.

While no acknowledging the reset devices have been shown, it is obvious that the brake control circuit could be supplied with such devices in the manner indicated, for example in the Howe Patent 1,604,098, above referred 90 to, whereby, if an acknowledging act were properly performed, a brake application would be avoided even though no appreciable voltage were induced in the secondary winding 17, and if a brake application were incurred, operation of the reset device would restore the 95 various parts to their normal positions and conditions, that is, the positions and conditions as shown in the drawing which are those existing under travel of the car in clear territory.

It should be noted that the secondary circuit, including relay MR, is energized, through voltage induced in a single winding 17, whereby a shorting out of the secondary 105 winding will result in a brake application, while with a bucking coil employed as is sometimes customary, the shorting out of such coil would result in a failure to incur a brake application, under conditions calling for such 110 an application, and thus endanger the safety of the train in question.

The above rather specific description of one form of the invention, is given solely by way of example, and is not intended, in any manner whatsoever, in a limiting sense. Obviously, the invention can assume many different physical forms, and is susceptible of numerous modifications, and it is intended to include, in this application, all such forms and 115 modifications as come within the appended claims.

Having described my invention, I now claim:—

1. In a train control system, a trackway 125 inductor controlled in accordance with traffic conditions ahead, a car carried receiver positioned to be inductively associated with the inductor, and including a primary core and a separate H shaped secondary core, a pri- 130

mary winding on the primary core, and a secondary winding on the cross bar of the H shaped secondary core.

2. In a train control system, a trackway inductor in the form of a single bar arranged parallel with the track and controlled in accordance with traffic conditions ahead, a car carried receiver positioned to be inductively associated with the inductor and including a primary core and a separate H shaped secondary core, a primary winding on the primary core, a secondary winding on the cross bar of the H shaped secondary core, and a train control device controlled by the secondary winding.

3. In a train control system, a wayside inductor in the form of a single bar of magnetic material and controlled in accordance with traffic conditions ahead, a car-carried receiver including separate primary and secondary cores, the secondary core having the general form of an H and the primary core being a bar, parallel to, and straddling, the secondary core, primary and secondary windings on the respective cores, the secondary winding being on the cross bar of the H , and a train control device controlled by the secondary winding.

4. In a train control system, a wayside inductor in the form of a single bar of magnetic material, means to control the inductor in accordance with traffic conditions ahead, a car carried receiver including separate primary and secondary cores, the secondary core having the general form of an H and the primary core being a bar parallel to, and straddling, the secondary core, and having down-turned ends extending substantially below the plane of the major portion of the secondary core, primary and secondary windings on the respective cores with the secondary winding on the cross bar of the H , and a train control device controlled by the secondary winding.

5. In a train control system, a wayside inductor in the form of a single bar of magnetic material with means for its control in accordance with traffic conditions ahead, a car carried receiver including separate primary and secondary cores, the secondary core having the general form of an H , the primary core being a bar parallel to, and straddling, the secondary core, primary and secondary windings on the respective cores with the secondary winding on the cross bar of the H , and a train control device controlled by the secondary winding, the legs of the H shaped secondary core each extending beyond the other, at one end, and having its other end bent downwardly.

6. In a train control system, a wayside inductor in the form of a single bar of magnetic material with means for its control in accordance with traffic conditions ahead, a car carried receiver including separate pri-

mary and secondary cores, with the secondary core having the general form of an H with the legs each extending beyond the other, at one end, and having their respective other ends bent downwardly, the primary core a bar parallel to, and straddling, the secondary core with down turned ends extending substantially below the plane of the H portion of the secondary core, primary and secondary windings on the respective cores with the secondary winding on the cross bar of the H , and a train control device controlled by the secondary winding.

7. In a train control system, a wayside inductor in the form of a single bar of magnetic material with means for its control in accordance with traffic conditions ahead, a car carried receiver including separate primary and secondary cores, the secondary core having the general form of an H , the primary core being a bar parallel to, and straddling, the secondary core with down turned ends on the primary core extending substantially below the plane of the H of the secondary core, primary and secondary windings on the respective cores, with the secondary winding on the cross bar of the H , the legs of the secondary H core each extending beyond the other, at one end, and having its other end bent downwardly whereby to have their downwardly bent ends lie in substantially the same plane as that of the downwardly bent ends of the primary core, and a train control device controlled by the secondary winding.

8. In a train control system, a receiver comprising, a primary core in the form of a bar having a body portion and ends with its ends bent at right angles to the body portion, a secondary core in the form of an H , symmetrically arranged below said body portion, and between said bent ends, of the primary core, each leg of the secondary core extending beyond the other, at one end, and being bent downwardly at the other end to lie in substantially the same plane as the ends of the primary core, and primary and secondary windings on the respective cores.

9. In a train control system, a receiver comprising, a primary core in the form of a straight bar with its ends bent at right angles thereto, a secondary core in the form of an H , symmetrically arranged below, and between the bent ends of, the primary core, with each leg of the secondary core extending beyond the other, at one end, and being bent at right angles to the body portion at the other end to lie in substantially the same plane as the ends of the primary core, a primary winding on the primary core, and a single secondary winding on the cross bar of the H shaped secondary core.

10. In a train control system, a receiver comprising, a primary core in the form of

a straight bar with its ends bent at right angles to the main portion, a secondary core in the form of an **H**, symmetrically arranged below, and between the bent ends of, the 5 primary core, each leg of the secondary core extending beyond the other, at one end, and being bent at right angles to the body portion at the other end to lie in substantially the same plane as the ends of the primary 10 core, primary and secondary windings on the respective cores, and a trackway inductor in the form of a single bar of magnetic material, with means for its control by traffic conditions, arranged to at times bridge across 15 the ends of the primary core.

11. In a train control system, a receiver comprising, a primary core in the form of a bar with its ends bent at right angles thereto, a secondary core in the form of an **H**, 20 symmetrically arranged below, and between the bent ends of, the primary core, each leg of the secondary core extending beyond the other, at one end, and being bent downwardly at the other end to lie in substantially the 25 same plane as the ends of the primary core, a primary winding on the primary core, a single secondary winding on the cross bar of the **H** shaped secondary core, and a trackway inductor, in the form of a single bar of 30 magnetic material, with means for its control by traffic conditions, arranged to at times bridge across the ends of the primary core.

In testimony whereof I affix my signature.
WILLIAM D. HAILES.
